UNITED STATES PATENT OFFICE.

ALONZO E. RHOADES, OF HOPEDALE, MASSACHUSETTS, ASSIGNOR TO THE DRAPER COMPANY, OF SAME PLACE AND PORTLAND, MAINE.

WARPING-MACHINE.

SPECIFICATION forming part of Letters Patent No. 624,541, dated May 9, 1899.

Application filed January 20, 1899. Serial No. 702,841. (No model.)

To all whom it may concern:

Be it known that I, ALONZO E. RHOADES, of Hopedale, county of Worcester, State of Massachusetts, have invented an Improvement 5 in Warping-Machines, of which the following description, in connection with the accompanying drawings, is a specification, like letters and figures on the drawings representing like parts.

10 It is advisable in all warping-machines to stop the winding of the yarn upon the beam when there is a predetermined length of yarn thereupon, and it is the usual practice to operate the measuring mechanism from a small 15 roll at the top of the warper and over which the yarns run; but there is always some slip with a device of this character, involving inaccuracy in the measuring.

My present invention has for its object the 20 production of means for effecting the measuring without such inaccuracy and for effecting the operation of the stopping means for the warper when the predetermined length of yarn has been wound upon the beam.

25 Various features of my invention will be hereinafter described, and particularly pointed out in the following claims.

Figure 1 is an end elevation of a warping-machine of usual construction. Fig. 2, on a 30 reduced scale, is a perspective view of the main frame, the fast and loose pulleys, the belt-shipper, and the well-known means for controlling the latter, to better enable my invention to be understood; and Fig. 3 is a perspective detail to be referred to.

35 Referring first to Fig. 2, the end frames A A', the fast and loose pulleys B B', the belt-fork b, mounted on a sliding rod b', the elbow-lever b² to effect longitudinal movement of the rod, the rock-shaft b³, having a treadle or foot-board B^X, Fig. 1, and a counterbalance-weight W, and the rocker-arm b⁴, fast on the rock-shaft and pivotally connected with and to operate the rod b', may be and are all of 40 usual or well-known construction, the operator starting the machine by depressing the foot-board B^X, as in Fig. 1.

The usual winding drum or cylinder D, Fig. 1, on which the core of the beam B¹⁰ rests and 45 is rotated to wind the yarn w upon it, has secured to its journal at one end a disk D',

having, as herein shown, an eccentric groove d to receive a roller or other stud d' on an arm d², fast on a short rock-shaft d³, mounted in the frame A', whereby the rotation of the 55 drum D will rock the shaft d³. On the outer end of the said rock-shaft is rigidly secured an upturned rocker-arm d⁴, to which is pivotally connected at d⁵ a pawl d⁶, adapted to engage and rotate, step by step, a ratchet-wheel c, forming a part of the measuring mechanism to be hereinafter described.

The starting and stopping shaft b³ has fast upon it, outside the frame A', an arm b⁵, Fig. 1, to which is connected at b⁶ the upturned 65 shipper-rod b⁷, extended through a suitable notched holding-plate b^X on the frame and provided with a shoulder b⁸ to engage the under side of the plate and maintain the stop-motion mechanism inoperative when the machine is running.

A knock-off lever b⁹, pivoted on the frame adjacent the plate b^X, is provided with a lug b¹⁰ to at times engage the shipper-rod b⁷ and release the shoulder from the holding-plate, 75 the upper end of the knock-off lever being slightly separated from the upper end of the shipper-rod, as shown.

The upper end of the rocker-arm d⁴ has pivotally mounted upon it at d⁷ a latch d⁸, (shown 80 separately in Fig. 3,) said latch being herein formed as a bent lever with one arm normally extending over the top of the knock-off lever b⁹ and provided with a laterally-extended toe d⁹, adapted to enter between the shipper-rod 85 and the knock-off lever when the machine is to be stopped automatically. The other arm of the latch is upturned at d¹⁰ and is acted upon by a pin or stud a^X, extended laterally from a normally-vibrating arm a, fulcrumed 90 at a' and vibrated in usual manner, said arm being common in warping-machines as forming a part of the stop-motion mechanism thereof. The vibrations of said arm and the rocker-arm d⁴ are so timed that ordinarily the 95 latch d⁸ will be maintained in inoperative position with its toe d⁹ above and out of engagement with the knock-off lever as the rocker-arm swings back and forth; but when the vibrator a is held from coming back the latch 100 is released, its toe d⁹ engages the upper end of the knock-off lever b⁹, and as the rocker-

arm d^4 swings back said lever b^9 will be rocked to release the shipper-rod b^7 . An extension 10 of the rocker-arm serves as a back-stop for the arm d^{10} of the latch and prevents it from 5 being thrown too far back.

Returning now to the measuring mechanism the ratchet-wheel c has an attached worm c' in mesh with a worm-gear c^2 , fast on an upright shaft c^x , supported in suitable bearings 10 on the frame and having at its upper end a worm c^3 , which drives the "warper-clock," as it is termed. This clock has a worm-gear c^4 in mesh with and rotated by the worm c^3 , and a worm c^5 , having a deep groove, is rotated by 15 and with the gear c^4 , there being a slot c^6 at the end of the groove. A finger c^7 , mounted to slide on a rod c^8 , travels in the groove and is held therein in any suitable manner, as by a weighted arm 15, bearing against the finger, 20 the finger dropping into the slot c^6 when it reaches the end of the groove in the worm c^5 . The upper end of the finger, beyond its fulcrum, has attached adjustably thereto by a set-screw 5 a stop, shown as a rod c^9 with a shoulder or head c^{10} , normally held in the position shown in Fig. 1, above a long roll or stud 25 a^2 , extended laterally from the vibrator a , so as not to interfere with the movement of the latter. When the finger c^7 reaches the end of 30 the groove in the worm c^5 , it drops into the slot c^6 , turning said finger on its fulcrum and permitting the head c^{10} of the stop to drop down behind the roll a^2 as the vibrator a moves to the right, Fig. 1, into dotted-line position and preventing the return movement 35 thereof. The stud a^2 is thus held away from the latch d^8 , so that on the forward swing of the rocker-arm d^4 the toe d^9 of the latch engages the upper end of the knock-off-lever b^9 , 40 turning the latter as the rocker-arm swings back, and thereby releasing the shipper-rod b^7 to effect the shifting of the belt and stoppage of the machine.

An eccentric f is mounted on a pivot f^x on 45 the frame A' , engaged by a strap f' , secured to or forming part of an elbow-lever $f^2 f^3$, the depending arm f^2 having a lateral lug f^4 beneath the pawl d^6 , the longer arm f^3 being shouldered at 8 and extended through a hole 50 18 in the shipper-rod. A handle f^5 is secured to the eccentric f to rotate the latter on its pivot f^x , and thereby move the elbow-lever in one or the other direction.

It is sometimes necessary or desirable to 55 run the drum D before the beam is applied and before the winding of the yarn is begun, and at such time the handle f^5 is turned to the right, Fig. 1, to move the eccentric-disk f on its pivot f^x , and thereby through the lug 60 f^4 lift the pawl, but at the same time the shoulder 8 operates to release the shipper-rod b^7 from its holding-plate. It is therefore necessary for the operator to keep the treadle B^x depressed so long as the machine is running with the clock mechanism inoperative, 65 so that the machine cannot run while the attendant is absent unless the ratchet-wheel c

is turning by the action of the pawl d^6 , the return of the disk f to the position shown in Fig. 1 being necessary before the shipper-rod 70 can engage its holding-plate.

By operating the measuring mechanism from the drum which drives the beam by surface contact there is practically no slip whatever, owing to the great weight of the beam. 75

When the disk f is in the position shown in Fig. 1, it will be manifest that if the arm f^3 of the elbow-lever is lifted the arm f^2 will be swung to the right and upward to release or lift the pawl. The free end of the arm f^3 80 is extended through the hole 18 in the shipper-rod b^7 , and when the latter is released from its holding-notch it rises, and thereby lifts the outer end of the arm f^3 , rocking the elbow-lever and releasing the pawl, as has 85 been described, so that movement of the shipper-rod into operative position effects the release of the pawl.

My invention is not restricted to the precise construction and arrangement herein 90 shown and described, as the same may be varied without departing from the spirit and scope of my invention.

Having fully described my invention, what I claim as new, and desire to secure by Letters 95 Patent, is—

1. In a warping-machine, stopping means, warp-measuring mechanism to effect the operation of said means when a predetermined length of warp has been wound, actuating 100 means for the measuring mechanism, and a device intermediate said actuating and stopping means, to maintain one operative when the other is inoperative, and vice versa.

2. In a warping-machine, a winding-drum, 105 measuring mechanism for the warp, means actuated by the drum to operate said mechanism, stopping means for the machine, operative by or through the measuring mechanism when a predetermined length of warp has 110 been wound, said means including a shipper-rod and its holding member, and a manually-controlled device to render inoperative the means for actuating the measuring mechanism and to maintain the shipper-rod out of 115 engagement with its holding member.

3. In a warping-machine, the winding-drum, measuring mechanism for the warp, a pawl and ratchet actuated by the drum, to operate the measuring mechanism, stopping means, 120 including a shipper-rod, a releasing device for the pawl, operated by said rod, and connections between the rod and the measuring mechanism, to release the former when a predetermined length of warp has been wound. 125

4. In a warping-machine, the winding-drum, warp-measuring mechanism actuated thereby, operating connections between them, stopping means, operative by or through said measuring mechanism when a predetermined 130 length of warp has been wound, said stopping means including a shipper-rod and its holding member, a device intermediate the shipper-rod and the connections between the

drum and measuring mechanism, to maintain the latter inoperative when the shipper-rod is disengaged from its holding member, and vice versa, a manually-operated controller for said device, and independent means to maintain the shipper-rod in inoperative position while disengaged from its holding member.

5. In a warping-machine, the winding-drum, warp-measuring mechanism actuated thereby, operating connections between them, stopping means, including a shipper-rod and its knock-off lever, a rocking arm, a normally

inoperative latch carried thereby, to engage and operate the knock-off lever, and latch-controlling means governed by the measuring mechanism and operative to release the latch when a predetermined length of warp has been measured.

10 In testimony whereof I have signed my name to this specification in the presence of two subscribing witnesses.
